Jas. A. Richmond

ATTORNEY.

UNITED STATES PATENT OFFICE

ARTHUR E. DAVENPORT, OF MAYWOOD, ILLINOIS

DRIP STOPPER

Application filed June 21, 1928. Serial No. 287,127.

The invention relates to pumps for dispensing lubricating oils and the like and more particularly to means for use in connection therewith to prevent dripping and so obviate conditions making for loss of prime and inaccurate measure. More specifically it is the aim of the invention to provide a simple attachment capable of application to all standard pumps and which operates in a positive manner to seal the outlet or nozzle against dripping.

The nature, characteristic features and scope of the invention will more readily be understood from the following description taken in connection with the accompanying drawings, forming a part hereof, wherein

Figure 1 is an elevational view of the drip stopper in operative position.

Fig. 2 is a similar view in inoperative position.

Fig. 3 is a detail, showing the valve.

Fig. 4 is a sectional plan view of the clamp.

Fig. 5 is a vertical sectional view through the connected parts.

According to the invention, the outlet or delivery pipe 5^a of a pump is equipped with a readily applicable delivery unit or nozzle 5 for the support and carriage of the drip stopper. It is understood that the nozzle 5, which is or may be of conventional or preferred form, is removably secured by means of screw threads to the delivery pipe 5^a, and is provided with a restricted delivery passage 16, as hereinafter referred to. The supporting means preferably consists of a sectional clamp embodying a pair of half rings 6 with aligning ears 7 apertured for the passage of securing devices for locking the clamp in place on the skirt portion 8 of the nozzle, the upper edges of the half rings being contoured, as by inwardly directed lips 9, to center the clamp and to put the weight of the latter and of the drip stopper on the nozzle. One of the half rings is formed or provided with a pair of spaced depending ears 10 having registered openings. A lever 11 has a short arm 12 at right angles to the longer arm which enters between the ears 10 and is pivotally secured as at 13. The arm 12 is formed

or provided with an offset or projection 14 terminating in a valve or stopper element 15 adapted to impinge upon and close the outlet of the oil delivery passage 16; and as a further assurance of effective sealing of the oil outlet the valve or stopper element is provided with a fabric or other appropriate sealing wafer 17. It will be understood that the drip stopper is effective in the down or horizontal position of the longer arm of the lever 11, the stopper being restrained against casual displacement by a weight or ball 18 carried by the lever. When oil is to be dispensed the longer arm of the lever is moved to substantially perpendicular position, it being understood that by reason of the offset arm 12, and the presence of an inclined slot 19 in the proximate clamp member, the lever is tilted sufficiently beyond the center of gravity to be restrained in its uplifted position by the weight of the ball.

Having described my invention, I claim:

1. A drip stopper for oil pumps, comprising the combination with the delivery unit, of a device pivoted adjacent the outlet thereof, said device having means on one side of the pivot adapted to bear upon and seal the outlet, and means on the other side of the pivot effective in a positive way to secure the sealing element in operative position or in inoperative position.

2. The combination with the outlet of an oil delivery unit, of a pivotally mounted external sealing element for the outlet, and a weighted lever having a circumscribed arc of movement to hold the sealing element in effective position or in inoperative position.

3. In combination with an oil delivery pipe, a delivery unit including a skirt element interfitting concentrically with the delivery pipe, a stopper pivotally supported by the skirt element and capable of an operative relation with the unit to cut off flow therefrom or an inoperative relation with such unit, and a lever for holding the stopper in either relation against casual displacement.

4. In combination with an oil delivery pipe, a delivery unit supported by said pipe and including a concentric skirt element, a clamp

carried by the skirt element, means for removably securing such clamp to the skirt, a pivoted stopper adapted to said unit and serving in one position to cut off flow therefrom, and a weighted lever for operating such stopper.

In testimony whereof I affix my signature.
ARTHUR E. DAVENPORT.
